DESIGN FOR A ROOM COOLER OF THE WINDOW TYPE

Lurelle Guild, New York, N. Y., and Harper Landell, Philadelphia, Pa., assignors to Carrier Corporation, Syracuse, N. Y., a corporation of Delaware

Application October 10, 1947, Serial No. 141,852

Term of patent 3½ years

(Cl. D62—4)

To all whom it may concern:

Be it known that we, Lurelle Guild, a citizen of the United States, residing at New York city, in the county of New York, State of New York; and Harper Landell, a citizen of the United States, residing at Philadelphia, county of Philadelphia, Commonwealth of Pennsylvania, have invented a new, original, and ornamental Design for a Room Cooler of the Window Type, of which the following is a specification, reference being had to the accompanying drawings, forming part thereof, in which

Figure 1 is a perspective view taken from the end that faces in a room of a room cooler of the window type embodying our new design;

Figure 2 is a sectional view illustrating the contour of the top surface of the room cooler;

Figure 3 is a sectional view illustrating the contour of the front louvres;

Figure 4 is a sectional view illustrating the contour of the side louvres; and

Figure 5 is a top plan view of the cooler on a small scale.

The side of the room cooler not shown is the same as the side of the cooler illustrated.

We claim:

The ornamental design for a room cooler of the window type, substantially as shown and described.

LURELLE GUILD.
HARPER LANDELL.
